(57) **CLAIM**

The ornamental design for a lamp shade, as shown and described.

DESCRIPTION

FIG. 1 is a perspective view of a lamp shade showing the present invention;

FIG. 2 is a front side elevation view thereof;

FIG. 3 is a side elevation view thereof;

FIG. 4 is another side elevation view thereof;

FIG. 5 is a top plan view thereof;

FIG. 6 is a bottom plan view thereof, wherein the light bulb and fixture are not shown and do not form any part of the claimed design; and,

FIG. 7 is another perspective view of the lamp shade. The broken lines illustrating the chain, wire and base structure are included to show environmental structures and form no part of the claimed design.
